United States Patent Office.

N. O. J. TISDALE, OF NEW ORLEANS, LOUISIANA.

Letters Patent No. 94,045, dated August 24, 1869.

IMPROVED MACHINE FOR CHARGING GAS-RETORTS.

The Schedule referred to in these Letters Patent and making part of the same.

To all whom it may concern:

Be it known that I, N. O. J. TISDALE, of the city of New Orleans, State of Louisiana, have invented a certain new and useful and improved Machine for Putting into Gas-Retorts the Proper Charge of Coal to be Carbonized; and I do hereby declare the following to be a full, clear, and exact description of the same, reference being had to the annexed drawing, making a part of this specification, on which—

Figure 1 is a perspective, and

Figure 2, a sectional view of said machine.

My invention is a mechanical organism, through the agency of which gas-retorts can be more expeditiously and properly charged with coal, and with less labor and cost than by any method hitherto known or practised.

This organism consists of an elongated shallow open box, in which is adjusted a movable and reversible web or link-bottom, or apron, and proper means for operating the same, that is sustained in a guide-way or sheath, in such manner as to have a reciprocating endwise motion, corresponding in its extent with the length of the retort, the said guide-way being supported on a proper frame or carriage on wheels, resting on a railway, so as to be movable, and therefore readily susceptible of being taken from one bench of retorts to another, and into the coal-store.

In other words, my invention is a machine which charges gas-retorts without further hand-labor than is requisite to place the coal in it, and then to cause the same to be discharged in the retort, the operation being effected with great economy of time and labor, as compared with any other mode that has hitherto been practised.

But my invention will be more quickly understood, both in respect of its mechanical construction and its mode of operation, by referring to the drawing, on which the same letters denote like parts at both the figures.

In the drawing—

A represents an ordinary gas-retort, as constructed in this country, in a detached state, the object of its delineation being to illustrate the manner in which my machine enters the same when loaded; and

B, what I denominate a guide-way, whose function it is to sustain the elongated shallow open box C, which, for purposes of distinction, I call a "charger," and also suitable mechanical appliances or means for operating the said charger and its reversible bottom D, which consists of a series of narrow strips, as shown, that are hinged together, in any usual manner and by any proper means, so as that the said bottom may be readily flexible—a necessary condition, as will hereafter be shown, to the successful working of my invention.

The guide-way B is fixed on a railway-carriage, moving through the retort-house upon a railway laid along the front of the fire-stack in which the retorts are set, in such manner as to bring the proximate extremity of the same very nearly in contact with the front of the mouth-piece of the retort.

On the carriage may be placed one or any number of my machines, accordingly as the number of retorts in a bench may vary, which are to be adjusted on the same at such heights and in such positions that each charger, resting in its guide-way, will have its bottom just sufficiently above the level of the bottom of the retort which is to be charged by it to enter said retort whenever the carriage is placed in position before the bench to charge the retorts therein. So worked in sets of three or five machines on one carriage, they can all be driven into the retorts, and withdrawn therefrom, by a single motion and at a single operation, simultaneously delivering their several charges, smoothly and accurately, and at any desired rate of speed.

As I do not claim the carriage, nor, in this application, any particular means for operating a number of my machines, I have not considered it necessary to show said carriage, nor any such means, on the drawing.

The guide-way B consists of two vertical sides b b', that are held together, and at a proper distance apart, according to the width of the retorts, by transverse screw-bolts c, that all occupy the same horizontal line, very near the lower edges of the sides b b', as shown on the drawing.

Just above the line of the bolts c, a ratchet, or toothed bar, d, is secured upon the interior surfaces of each of the sides b b', as shown; and just above this bar, a projecting slide or rail, e, to subserve a purpose hereafter to be indicated.

The ratchet-bar d, and the rail e above it, are parallel to each other, and both occupy horizontal planes or lines.

On top of each of the sides b b' is another rail, g g, projecting inwardly, as shown, and occupying a parallel relation with respect to e.

The continuity of each of these upper rails g is broken by traps or hinged sections g' g'', near their outer extremities, and from the outer end of the openings under said traps, the rails g g are connected to the rail e, by inclined bars or rails h. The object of this connection will be presently shown.

Nor do the rails g g extend the whole length of the guide-way B. They terminate near the inner ends of the guide-way, by which I mean the ends next the retort, so as to provide an opening, i, upon each side of said guide-way, for a purpose to be indicated when I come to describe the operation of the machine.

The inner ends of the openings *i* are guarded by the projecting stoppers *s* *t*.

The rails *e* and *g* may be made of angle-iron, riveted or bolted to the vertical sides *b* *b*', or in any other proper manner; and in some cases the ratchet-bar *d* and the rail *e* may be formed of one piece.

I do not confine myself to any special mode of constructing the rails, nor, indeed, any other part of the guide-way *B*, always provided there be no deviation from the general principles as herein described, and shown on the drawing, and that the rail *e* presents two distinct faces, the one a little above the other, after the manner of a terrace.

At the outer end, and near the upper edges of the sides *b* *b*' of the guide-way *B*, a pulley, *E*, is secured, as shown, in proper journals; and to the axis of this pulley, which is extended with this view, a crank, *f*, is firmly fastened. This pulley, or any equivalent thereof, constitutes a means for operating the charger, either by hand, steam, or other power.

Within the guide-way *B*, is fitted the charger *C*, which, in its external peculiarities of construction, resembles very closely the guide-way itself; that is to say, it is composed of two vertical sides *2*, that are held together, at any given or desired distance apart, by transverse screw-bolts *1*.

These bolts pass through bars *e*', and secure them on the opposite internal surfaces of the vertical sides *2* of the charger *C*, in the same horizontal plane, to serve as supports for the reversible bottom or apron *D*, which, when occupying the position shown at fig. 1, and therefore ready to receive a charge of coal, rests on said bars, and is sustained by them.

The reversible bottom or apron is provided with a bracket-termination, *k*, at its outer end, that is so constructed as to afford a handle, by which it can be readily seized by hand when the said bottom is to be drawn into position, as shown at fig. 1, or for loading, and also to take over the catches *3*, to hold the same immovably in position.

At the end of the charger *C*, next to the retort, the bottom *D* passes over a rectangular pulley, not shown on the drawing, but whose axis is shown at *4*, the flat faces on said pulley corresponding in width with the width of the sections or strips which, hinged together, constitute the said bottom *D*, and then pass between the bars *e*' and flanches projecting from the two sides *2*, at their bottom edges, inwardly at right angles to the planes of the said sides, sufficient space between said bars and flanches being provided for this purpose, and is secured to a chain, *o*, that leads, and is connected to the pulley *F*.

This pulley is provided at each of its ends with a cog-wheel, *l*, in which the cogs are of proper size to mesh in the teeth or cogs of the bars *d*, and outside these wheels, with circular racks, in which the pawls *m* take, and prevent the pulley from retrorotating in the operation of reversing the bottom to deliver the coal in the retort.

This pulley is not mounted in the sides of the charger, but in a frame, *n*, projecting from the end of the latter, as shown, and which is so connected with the two sides thereof as to have a certain measure of up-and-down vibration at the point at which the pulley has its journals, with the view to adapt the latter to move on the two distinct planes represented by the rails *g* and the rails *e*, with equal facility.

The frame *n* may be constructed as shown, or in any other manner which will accomplish the same object.

An extension of the axis of the pulley *F* outside the frame *n*, at both its ends, affords a means of putting on the rollers *p*, or their equivalents, to sustain the said pulley on the rails *g* and *e*, accordingly as, in the operation of the machine, it rests on the one or the other. The diameter of the rollers *p* should be

just a shade less than the distance or space between rails *g* and *e*, so as to provide a means for holding the pulley *F* down when it rests on rails *e*, and hence of securing the meshing of the cog-wheels *l* with the ratchet-bars *d*.

To the front end of the frame, a cord or chain, *q*, is fastened, which being put around the pulley *E* two or three times, to prevent slipping, is carried underneath the charger and over the pulley *G*, and then back to the outer end of the charger, where it is fastened to it by means of a fixed projecting cross-bracket, *t*, or some equivalent contrivance.

A moderate degree of tension being always kept on the cord *q*, it is obvious that a rotation of the pulley *E* will move the charger, with all its adjuncts, in one or the other direction, accordingly as the rotation of said pulley is in the one direction or the other, to the extreme limit allowed by the stoppers *i* and *s*.

In order to facilitate the movement of the charger over the floor or bottom of the retort, and in the guide-way, small wheels, *w*, are placed, at proper intervals apart, outside the vertical sides of the same, as shown, which, resting on the lower section of the terrace-rail *e*, and having a diameter only sufficiently less than the space between said rails and the upper rails *g* to permit of their free action, constitute a means also for holding the charger in position when it is in the guide-way *B*.

The diameter, and the rotation by means of the cog-wheels *l*, of the pulley *F*, are so calculated and adjusted as to pull the movable bottom or apron *D* over the roller whose axis is marked *4*, at a rate of speed precisely corresponding with the movement of the charger as it is drawn back into the guide-way, so as to deposit the charge in the retort with precise uniformity of depth throughout the whole extent or space within which it is desired to put it.

If a more rapid delivery of the charge should be desired, however, so as to deposit it in a shorter space in the retort than it occupied in the charger, it can be done by increasing the diameter of the pulley *F*, so as to give a more rapid motion to the bottom than to the charger.

My machine is made of wrought-iron, and as light as is compatible with a due regard to strength; and as before remarked, it may be very considerably modified in one or all its parts, and also in its general arrangement, without in the slightest degree changing its *modus operandi*, which I now proceed to explain.

Supposing the machine, in single or multiple form, to be properly placed on a carriage, resting on a railroad extending from the coal-store along the front of the fire-stack, whatever may be the number of benches of retorts therein, the charger is put in that position in the guide-way which will bring the rollers *p* in contact with the stoppers *s* and the bracket *k* of the reversible bottom *D* over the catches *3*.

The charger or chargers are now filled with the desired quantum of coal, and the carriage placed in front of the bench to be charged, in such wise as to bring a charger in line with each of the retorts therein, substantially as shown at fig. 1.

This being done, the pulley *E* is put in motion, and through the agency of the cord *q*, forces the charger into the retort and out of the guide-way, until the rollers reach the openings *i*, through which, from the gravity of the pulley *F* and its appliances, they instantly fall upon the lower rail *e*, carrying, of course, with them the pulley *F*, and the cog-wheels *l*, which latter at once come into connection with the cog or ratchet-bars *d*. The proportions of the parts are so adjusted that when this takes place, the charger has attained the limit of its penetration into the retort.

The direction of the rotation of the pulley *E* is now reversed, and the charger begins to recede from the retort, and, in doing so, puts the pulley *F* in motion

by means of the cog-wheels *l*, and winds up the chain *o*. This draws the bottom *D* over the pulley at *4*, and thus reverses the same, and deposits the coal in the retorts, in even and regular measure, as fast as the charger moves out of them.

In the reversal of the bottom *D*, as above described, it is drawn between the bar *e* and the projecting flanges at the bottom edges of the sides *2* of the charger, which latter support it on its longitudinal edges, and thus prevent it from sagging or falling down below the bottom of the charger.

The length of the ratchet-bar *d* is calculated with reference to the extent to which the bottom is to be reversed, so that the pulley *F* passes beyond these bars at the instant the charge is delivered.

To prevent the bottom *D* passing entirely off its upper plane, the catches *5* are so placed as to take against the bracket *k* the moment the charge has been delivered and the ends of the ratchet-bars have been passed by the pulley *F*. Arriving at the inclined bars *h*, the pulley *F* ascends the same, the light-traps *g' g''* interposing no appreciable resistance until the rollers *p* once more rest upon the rails *g*, the traps falling back into their places as soon as the said rollers ad-

vance sufficiently beyond the openings to allow them to do so.

The pawls *m* are now disengaged from their racks, in order to allow of a reverse revolution of the pulley *F*, and then the bottom *D* is pulled by hand, by means of the bracket *k*, back to its original position, and the machine is ready for another operation, and so on indefinitely.

Having thus described my invention,

What I claim, and desire to secure by Letters Patent, is—

1. The guide-way *B*, when constructed substantially as herein described, for the purpose set forth.
2. The charger *C*, when provided with the reversible bottom or apron *D*, and constructed and operating substantially as and for the purpose set forth.
3. The combination of the guide-way *B* and the charger *C*, when these parts are constructed, arranged, and conjointly operate substantially as described, for the purpose set forth.

N. O. J. TISDALE.
